UNITED STATES PATENT OFFICE.

CECIL ALDIN, OF SOUTHFIELDS, HENLEY UPON THAMES, ENGLAND,
ASSIGNOR TO LAWRENCE & JELLICOE, LTD., OF LONDON, ENGLAND.

DESIGN FOR A FRIEZE FOR WALL-COVERINGS.

No. 38,245.

Specification for Design.

Patented Sept. 18, 1906.

Application filed July 10, 1906. Serial No. 325,545. Term of patent 7 years.

To all whom it may concern:

Be it known that I, CECIL ALDIN, a subject of the King of Great Britain, residing at Southfields, Henley upon Thames, England, have invented a new, original, and ornamental Design for a Frieze for Wall-Coverings, of which the following is a specification.

My design consists of a continuous frieze shown in the accompanying drawing in several sections.

I claim—

The ornamental design for a frieze for wall-coverings, as shown.

CECIL ALDIN.
